attorney.

UNITED STATES PATENT OFFICE.

LESTER LE ROY SMITH, OF LYNN, MASSACHUSETTS.

FIRE-EXTINGUISHER.

1,261,311.

Specification of Letters Patent.

Patented Apr. 2, 1918.

Application filed January 24, 1917. Serial No. 144,271.

To all whom it may concern:

Be it known that I, LESTER LE ROY SMITH, a citizen of the United States, and a resident of Lynn, in the county of Essex and Commonwealth of Massachusetts, have invented 5 certain new and useful Improvements in Fire-Extinguishers, of which the following is a full, clear, and exact specification.

In fire extinguishing instrumentalities of 10 the type wherein air is pumped into a reservoir of chemicals in order to force the latter in a spray upon the fire, the outlet is adapted to be kept in constant communication with the chemicals in the reservoir no matter 15 at what angle the latter may be held.

For accomplishing this, the outlet communication member is rotatably supported to gravitationally swing to whichever side of the cylindrical reservoir is lowermost. 20 Inasmuch as said member must be comparatively slender and light, it occasionally fails to begin its descent into the fluid chemicals.

The object of this invention is the construction of such an outlet communication 25 member as shall be of maximum certainty of actuation, and the effecting of certain other improvements in details of construction hereinafter set forth.

Referring to the drawings forming part 30 of this specification, Figure 1 is a central longitudinal section of a fire extinguisher gun embodying my improvements. Fig. 2 is an enlarged detail of the pump valve. Fig. 3 is an enlarged sectional view of the 35 outlet valve, and Fig. 4 is a plan view of the same. Fig. 5 is a section through the line X—X in Fig. 1.

The reservoir 1 is cylindrical in form, with a head 2 rigidly supporting an air 40 pump axially within the cylinder. In the pump cylinder 3, is a plunger 4 and a plunger rod 5 connected with a handle 6 exterior of the gun.

At the inner end of the pump cylinder 3 45 is a head 8 having an outlet 7 for the air from the pump to the reservoir, the outlet being provided with a check valve 9 of a well known type. The inner end of the plunger rod 5 is made tubular for a short 50 distance, as at 10, controlled by a check valve 11. To prevent any possible leakage of air from within the reservoir 1 when the fire extinguisher is not in use, and so to keep it constantly ready for instant ejection of the 55 chemical within the reservoir, a valve 12 is located in the pump at a point to close the

outlet 7, but provided with three or four resilient arms 13 disposed for normally retaining the valve out of engagement with the outlet, each arm having a foot 14 resting 60 against the interior of the pump cylinder 3 for the purpose of keeping the valve in place.

The plunger rod 5 is provided with an ear 15 adapted to be engaged with the finger 16 and to lock the plunger at a point where 65 its pressure against the valve 12 forces the latter to tightly close the outlet 7.

The reservoir 1 being suitably filled with the extinguisher fluid, the air pumped therein at a high pressure causes the fluid to be 70 ejected with great energy from the nozzle 20, located at the end of the reservoir opposite to the handle 6. For causing the fluid always to be between the compressed air and the conduit leading to the nozzle, several 75 different arrangements have been devised, each of which is open to criticism. The following is my preferred construction:

A tubular spindle 21 has one end closed and formed as a slender trunnion 22 rotatably supported in a bearing 23 in the pump head 8. Its other end is enlarged, as at 24, to rotatably fit the tubular stud 25 which projects from the thimble 26 preferably formed as a part of the reservoir head 27, 80 the interior of the spindle 21 and of the stud 25 being in alinement with each other, and at the axial center of the cylinder 1. From the tubular spindle 21 a tubular arm 29 projects radially, and is adapted to communicate with and to support at its outer end a tube 30 parallel with the axis of the cylindrical reservoir and closely spaced from the latter's interior surface. At each end of the tube 30 is a valve 31 coöperating with a 85 valve seat 32, the valves being joined by a slender rod or wire 33, so that the elevation of either end of the reservoir above the level of the other end will cause the valves 31 to descend by gravity and close the upper inlet 90 to the tube 30 and open its lower inlet. This keeps an open end of the intake tube 30 immersed in the fluid at all times no matter what the angle at which the reservoir is held.

The fluid ejected out through the tube 30, 105 arm 29, tubular spindle 21 and tubular stud 25, passes therefrom through the nozzle 20 and is thrown to a distance of many feet, often to a point seven or eight yards away.

The valve 12 for keeping the air confined 110 under heavy pressure within the reservoir from escaping through the pump 3 has al-

ready been described. For closing at will the exit through the nozzle 20, a valve 34 is located within the thimble 26, such valve being connected with a cylindrical portion 5 35 (Figs. 3 and 4) loosely slideable within the thimble, and designed to be pressed into a closing engagement with the passage through the tubular stud 25 by screwing the nozzle 20 inward, the latter being actuated 10 by a cap 36 rigid therewith. By applying a rotative action upon the periphery of the cap, which may be knurled for the purpose, the nozzle 20 is screwed in or out and the valve 34 correspondingly affected, holes 37 15 being made through the portion 35 to give free exit to the fluid when the valve slides away from its engagement with the stud- passage. Since the valve 34 is between the nozzle and the reservoir, the nozzle may be 20 made to turn freely in the thimble 26 without fear of leakage thereat when the reservoir is put away with a heavy head of air therein.

The tube 30 being comparatively light and 25 liable at times to be rendered somewhat buoyant by air trapped in it, I have provided means for both initiating and hastening its descent into the fluid, should it be taken up and held with the tube uppermost 30 in the reservoir. To this end, the hollow head 24 of the tubular spindle 21 is provided with an arm 39 having branches 40 adapted to loosely embrace a heavy ball 41 which is adapted to freely travel in the circular race- 35 way 42 formed by the outer surface of the thimble 26 and the inner surface of the head 27. When the ball is uppermost, it is in very unstable equilibrium and will instantly begin to roll down about the thimble. Before 40 it has gone far, it collides with one of the arm-branches 40 and by its impact causes the arm and parts connected therewith to turn and descend to their lowermost positions.

45 To insure an air-tight engagement between the hollow head 24 and the conical end of the tubular stud 25, I provide a small plug 44 slidably supported in the bearing 23 and pressed against the end of the trun- 50 nion 22 by a spiral spring 45.

In use, the reservoir 1 is taken from its support, its nozzle 20 directed toward the conflagration to be extinguished, and the cap 36 turned until the fluid jets from the 55 nozzle with the force desired. If the stream is not as strong as it should be, or if it begins to fail, the plunger rod 5 is turned to release its ear 15 from the catch 16 and the handle 6 suitably actuated until 60 the required air pressure in the reservoir is fully reached. This action may be continued even while the stream is being directed upon the fire.

What I claim is:

65 1. A fire extinguisher comprising a reser-

voir for the extinguisher fluid, means for generating pressure in the reservoir, an outlet for the reservoir, a rotatable intake for the outlet, and a freely rotatable weight 70 loosely connected with the intake to impart a moving shock thereto after the weight has begun to move.

2. A fire extinguisher comprising a reser- 75 voir for the extinguisher fluid, means for generating pressure in the reservoir, an outlet for the reservoir, a rotatably supported intake for the outlet, an arm rigid with the intake, and a weight loosely carried at the end of the arm, whereby an initial movement of the weight forces the rotatable intake to begin its rotation to a lowermost point in the reservoir.

3. A fire extinguisher comprising a reser- 80 voir for the extinguisher fluid, means for generating pressure in the reservoir, an outlet for the reservoir, a rotatably supported tubular spindle communicating with the outlet, tubular branches rigid with the spindle and communicating therewith, the ends of 85 said branches being closely spaced from the sides of the reservoir, a terminally forked arm rigid with the spindle, a ball loosely carried between said forks, and a raceway partially supporting the ball.

4. A fire extinguisher comprising a cylind- 90 rical reservoir, means for generating pressure therein, the cylinder having a head provided with an inwardly projecting tubular stud, an outlet communicating with the tubular stud, a tubular spindle having a 100 hollow head turning on said stud, means for rotatably supporting the opposite end of the spindle, and a tube supported by and communicating with the spindle and having its ends close to but spaced from the sides of 105 the reservoir.

5. A fire extinguisher comprising a cylind- 110 rical reservoir, means for generating pressure within it, the reservoir having a head formed with an internally threaded thimble having a tubular stud, a tubular spindle rotatably supported at one end by the stud, a support for the other end of the spindle, branches in communication with and rigidly supported by the spindle with their ends 115 spaced from the sides of the reservoir, and an externally threaded nozzle turning in said thimble and communicating with said tubular stud.

6. A fire extinguisher comprising a reser- 120 voir having an outlet and a tubular stud in communication with the outlet, a tubular spindle having a hollow head turning on the tubular stud, branches supported by and in communication with the spindle, a bearing 125 for the end of the spindle opposite to the hollow head, a plug slidably in the bearing, and a spring in the latter pressing the plug and spindle toward the tubular stud.

7. A fire extinguisher comprising a reser-

voir, a pump and plunger within the reservoir, the pump having an outlet port to the reservoir, and a valve within the pump adapted to be pressed by the plunger into closing engagement with the outlet port, said valve having a plurality of resilient arms for normally supporting it out of said engagement.

8. A fire extinguisher comprising a reservoir, a pump and plunger within the reservoir, the pump having an outlet port to the reservoir, and a valve within the pump adapted to be pressed by the plunger into closing engagement with the outlet port, said valve having a plurality of resilient arms for normally supporting it out of said engagement, each of said arms having a foot

parallel with and pressed into close contact with the inner surface of the pump.

9. A fire extinguisher having a head provided with an internally threaded thimble having an outlet thereto from the reservoir, a tubular externally threaded nozzle turning in said thimble, and a valve formed with a cylindrical portion loosely fitting within the thimble and movable with the nozzle into closing engagement with said outlet, said cylindrical portion being formed with holes for the passage of the reservoir's contents through it.

In testimony that I claim the foregoing invention, I have hereunto set my hand this 22nd day of January, 1917.

LESTER LE ROY SMITH.
